UNITED STATES PATENT OFFICE.

OTTO PETERMANN, OF GROTON, NEW YORK, ASSIGNOR TO CORONA TYPEWRITER COMPANY, INCORPORATED, A CORPORATION OF NEW YORK.

TYPE-WRITING MACHINE.

1,121,087.

Specification of Letters Patent. Patented Dec. 15, 1914.

Application filed September 15, 1910. Serial No. 582,217.

To all whom it may concern:

Be it known that I, OTTO PETERMANN, a citizen of the Republic of Switzerland, and a resident of Groton, county of Tompkins, 5 and State of New York, have invented certain new and useful Improvements in Type-Writing Machines, of which the following is a full, clear, and exact description.

This invention relates more particularly 10 to work tables for typewriting machines and to means for moving the table toward and away from the platen.

The primary object of the invention is to provide simple and efficient means where- 15 by the work table of typewriter carriages may be moved in such a way that a feed roll mounted upon the table may be made to engage and rotate with the platen to feed the work sheet or be disengaged there- 20 from to permit the work sheet to be readily and properly positioned about the platen.

Another object of the invention is to pro- 25 vide simple means whereby the work table may be made of a single piece of sheet metal and pivoted to a part of the carriage in such a way that the said work table can be quickly moved on its pivot from the end of the carriage.

The invention will be hereinafter more 30 particularly described with reference to the accompanying drawings, which form a part of this specification, and will then be pointed out in the claims at the end of the description.

In the drawings, Figure 1 is a transverse section through the carriage and platen, 35 taken on the line I—I of Fig. 3. Fig. 2 is a transverse section taken on the line II—II of Fig. 3. Fig. 3 is a sectional plan view 40 of a part of the carriage, partly in elevation, with the platen removed; and Fig. 4 is a transverse section, showing means for rotating the platen and for releasing the 45 detent or pawl which normally engages the teeth of the platen ratchet wheel to prevent backward movement thereof.

The carriage 10 may be variously constructed and may be used in connection with various forms of typewriting machines. As 50 shown, the frame 11 has a horizontally ar- ranged base 12 and guide rails 13 and is adapted to move along a carriage bed, and held to rotate in the ends 14 of the carriage frame is a platen 15. The platen 15 55 may have a ratchet wheel, as 16, shown

partly in full and partly in dotted lines in Fig. 4, and adapted to engage this ratchet wheel is a pawl 17 carried by a lever 18. This lever 18 is pivoted to the shaft 19 of the platen and is normally pressed in one 60 direction by a spring 20, and said pawl is limited in its movement by an adjustable stop 21 mounted upon the carriage frame and which, with the pawl 17 and lever 18, forms a part of one form of line-spacing 65 mechanism. The parts thus far described may be of the usual or of any preferred construction.

A plate 22, forming a work table, is ar- ranged under the platen 15 and this work 70 table has its body portion 23 curved to fit about the platen for a part of its circum- ference and said work table extends rear- wardly and has an outwardly and down- wardly projecting portion or flange 24 to 75 adapt the work sheet to be readily slipped along the table and about the platen. At or near the forward portion of the work table is a feed roll 25. This roll is much smaller than the platen and is divided into 80 two parts or members 26 and 27. These parts may be of rubber or similar material and may have a shaft 28 which passes through the parts 26 and 27 and which ex- tends beyond the same to form bearing 85 portions 29. The table is slotted, as at 30, to permit the feed roll 25 to pass there- through so that the parts 26 and 27 will engage the surface of the platen and said work table has integral bearing portions 90 31, which project outward and form seats for the parts 29 of the shaft 28. The roll as thus arranged has a proper bearing on the work table and cannot be removed ex- cept by removing the platen or forcing the 95 work table far enough away from the platen to permit the roll to be taken out from above, and said means also permits the work table to be readily stamped or formed in a single piece. 100

To move the work table to release the feed roll from the platen so that the work sheet may be passed readily about the platen and properly positioned, I cut away part of the work table to form two arms or parts 32 on 105 opposite sides thereof and these parts are held to rock on the base plate 12 by means of screws 33 or otherwise, though instead of the arms 32 being integral with the work table, they may be separate therefrom and 110

may be of heavier material if so desired. A rod, as 34, extends lengthwise of the carriage and is journaled in the ends of the carriage frame 14 and said rod has a finger 5 or handle portion 35 by which it may be rocked in the frame. This rod is cut away to form cams or cam parts, as at 36, and normally resting in these cam parts 36 are the outer ends of the arms 32. The normal 10 position of the rod 34 is that shown in the drawings and when rocked in its bearings, the cam parts 36 will raise the arms 32 and this will throw the forward portion with the feed roll 25 away from the platen and will 15 hold the same in this position until the arms 32 again rest upon the cut away parts 36, there being one or more springs, as 37, arranged in recessed ends of adjustable screws 37^a located in the carriage plate or 20 base 12, which springs have their upper ends engaging the under surface of the work table and tending normally to force the feed roll into engagement with the platen.

25 While I show special line-spacing mechanism for rotating the platen and means whereby the detent for the line-spacing ratchet may be released, such features form no part of the present invention, the line-spacing mechanism being substantially the same as that disclosed in the application to Marshmann W. Hazen, Sr. No. 499,874, filed June 3, 1909.

From the foregoing, it will be seen that a 30 simple and efficient work table for a carriage is provided; that said work table may be made of a single piece of sheet metal; that simple means is provided whereby the work table may be held in such a way that it may 35 be moved from or toward the platen; that simple means is provided for mounting the feed roll on the work table; and that simple means is provided for moving the work table and feed roll away from the platen.

40 Having thus described my invention, I claim as new and desire to secure by Letters Patent:—

1. In a typewriter, the combination of a carriage having a base plate, a platen mounted in the carriage, a work table made of a single piece of metal, a feed roll mounted on said work table, integral arms projecting rearward from the work table below the main body thereof and supported directly 50 on the base plate, means for holding the arms to the base plate to adapt the same to rock thereon, springs interposed between the base plate and the table and normally forcing the forward portion of the table with 55 the feed roll toward the platen, and means engaging the arms at the rear portion thereof to move the work table and force the feed roll away from the platen.

2. In a typewriter, the combination of a 60 carriage having a base plate, a platen mount-

ed in the carriage, a work table made of a single piece of metal, a feed roll mounted on said work table, integral arms projecting rearward from the work table below the main body thereof and supported directly on the base plate, means for holding the arms to the base plate to adapt the same to rock directly thereon, and means for moving the feed roll toward and from the platen.

3. In a typewriter, the combination of a 70 carriage having a base plate, a platen mounted in the carriage, a work table, a feed roll mounted on said work table, arms projecting rearward from the work table below the main body thereof and supported directly on the base plate, means for holding the arms to the base plate to adapt the same to rock thereon, screws located in the base plate, springs seated in the screws and normally forcing the forward portion of the 75 work table with the feed roll toward the platen, and a rod having cam portions engaging the arms at the rear portion thereof to move the work table and force the feed roll away from the platen. 90

4. In a typewriter, the combination of a carriage having a base plate, a platen in said carriage, a work table shorter than the platen adapted to rock directly on the base plate, a feed roll mounted in the table, and means engaging a part of the work table to rock the table and to carry the feed roll away from the platen. 95

5. In a typewriter, the combination with a carriage having a base plate, of a platen mounted in said carriage, a work table having a curved body portion and provided with a downwardly-extending flange at the rear thereof and with arms located at opposite sides and formed integral therewith, means for holding the work table to rock on the base plate, said work table having depressed portions projecting downward and forming bearings, a feed roll journaled in said bearings and normally engaging the platen, and means engaging the arms for disengaging the feed roll from the platen. 105

6. In a typewriter, the combination with a support, of a platen mounted in said support, a work table, a feed roll mounted on said work table, said work table being movably held to the support, springs normally forcing the work table toward the platen to cause the feed roll to engage the platen, arms projecting 110 rearwardly from the work table, a rod extending lengthwise of the carriage and having parts thereof cut away to form cam portions adapted to engage said arms, and a handle on the rod for rocking the same to 115 move the work table on its pivots and to release the feed roll from the platen. 120

7. In a typewriter, the combination with a carriage having a base plate, of a platen mounted in said carriage, a work table, a 125

- feed roll mounted on said work table, said work table being movably held to rock directly on the base plate, a rod extending lengthwise of the carriage and having 5 cam means adapted directly to engage a part of said table, and means for rocking the rod to move said table and release the feed roll from the platen.
8. In a typewriter, the combination with 10 a support having a horizontally extending base plate, of a platen mounted in said support, a work table, a feed roll mounted on said work table, said work table being held to rock on said plate of the support, springs 15 adjustably held in the base plate for normally forcing the work table toward the platen to cause the feed roll to engage the platen, and means for moving the table to disengage the feed roll from the platen.
9. In a typewriter, the combination with 20 a carriage having a base plate, of a platen mounted in said carriage, a work table, a feed roll mounted on said work table, said work table being held to rock on the base 25 plate, springs normally forcing the work table toward the platen to cause the feed roll to engage such platen, screws arranged in the base plate and forming seats for the springs, arms projecting rearwardly from 30 the work table, and a rod extending lengthwise of the carriage and having cam portions adapted to engage said arms and disengage the feed roll from the platen.
10. In a typewriter, the combination with 35 a support, of a platen mounted in said support, a work table, a feed roll mounted on said work table, said work table being held
- to rock on the support, arms projecting rearward from the work table, a rod extending lengthwise of the carriage and having 40 parts thereof cut away to form cam portions adapted to engage said arms, and means on the rod for rocking the same to disengage the feed roll from the platen.
11. In a typewriter, the combination of a 45 carriage having a horizontally arranged base plate, and a work table adapted to rock directly on the flat upper surface of said plate.
12. In a typewriter, the combination of a 50 carriage having a base plate, a platen mounted on said carriage, a work table supported on and adapted to rock directly on said plate, and a feed roll supported directly on the table from above and adapted to engage 55 said platen.
13. In a typewriter, the combination of a carriage having a horizontally arranged base plate, a platen mounted on said carriage, a work table having cut away parts 60 and depressed portions forming bearings and adapted to rock directly on the base plate, a roll journaled loosely in said bearings, and adapted to engage the platen and removable from the work table from the 65 upper surface thereof, and means for moving the table to force the roll away from the platen.

This specification signed and witnessed
